UNITED STATES PATENT OFFICE

147,933

DESIGN FOR A COMBINATION HANDLE AND CONTROL VALVE FOR FIRE EXTINGUISH- ERS OR THE LIKE

John H. Stroop, New York, N. Y.

Application June 6, 1946, Serial No. 130,449

Term of patent 14 years

(Cl. D16—2)

To all whom it may concern:

Be it known that I, John H. Stroop, a citizen of the United States, residing in New York, in the county of New York, in the State of New York, have invented a new, original, and ornamental Design for a Combination Handle and Control Valve for Fire Extinguishers or the like, of which the following is a specification, reference being had to the accompanying drawing, forming a part thereof:

Figure 1 is a side elevational view of one side of a combination handle and control valve for fire extinguishers or the like embodying my new design;

Figure 2 is a side elevational view of the other side thereof.

Figure 3 is a top plan view; and
Figure 4 is an end view thereof.

I claim:

The ornamental design for a combination handle and control valve for fire extinguishers or the like, substantially as shown.

JOHN H. STROOP.
